(57) **CLAIM**

I claim the ornamental design for a self-adhering bead device, as shown and described.

DESCRIPTION

FIG. 1 is a front elevation view of a self-adhering bead device showing my new design;

FIG. 2 is a side view of the self-adhering bead device of FIG. 1;

FIG. 3 is another side view of the self-adhering bead device of FIG. 1;

FIG. 4 is a bottom view of the self-adhering bead device of FIG. 1;

FIG. 5 is a top view of the self-adhering bead device of FIG. 1;

FIG. 6 is a rear side view of the self-adhering bead device of FIG. 1; and,

FIG. 7 is a front side view of the self-adhering bead device of FIG. 1.

The self-adhering bead device is shown with a symbolic break in its length. The appearance of any portion of the self-adhering bead device between the break lines forms no part of the claimed design. The broken lines in the drawings represent portions of the self-adhering bead device and form no part of the claimed design.
